UNITED STATES PATENT OFFICE

ROBERT FEISLY, OF LAUSANNE, SWITZERLAND, ASSIGNOR TO THE FIRM: ELEKTRIZITATSGESELLSCHAFT "SANITAS" M. B. H., OF BERLIN, GERMANY

RÖNTGEN APPARATUS

Application filed April 12, 1926, Serial No. 101,475, and in Switzerland April 18, 1925.

My invention relates to improvements in Röntgen apparatus, and more particularly in apparatus for diagnostic examination and for taking photographs by means of Röntgen rays. Apparatus of this class such as are now in use are provided with means for preparing the exposure for instance replacing the fluorescent screen with a Röntgen box containing a sensitized plate, and elevating the heating of the Röntgen tube to the degree corresponding to photography; and with means for making the exposure. The operation of all of the said means requires much care and it takes much time. Further, by reason of the complicated mechanism the attendant is liable to make erroneous manipulations. The object of the improvements is to provide an apparatus which can be quickly and easily operated, and which avoids any errors in the operation. With this object in view my invention consists in providing a time switch in connection with a controlling hand switch, the hand switch being at first set for throwing the examination apparatus into operation. If it is desired to make an exposure the hand switch is set into position for setting the Röntgen box into operative position and thereafter exposing the sensitized plate, the time for the exposure, which ordinarily is only a fraction of a second, being determined by setting the time switch.

For the purpose of explaining the invention an example embodying the same has been shown in the accompanying drawings, in which the same reference characters have been used in all the views to indicate corresponding parts.

In said drawings,

Fig. 1 is a perspective elevation showing the switch apparatus,

Fig. 2 is a sectional elevation taken on the line 2—2 of Fig. 1 and showing the controlling hand switch,

Fig. 3 is a sectional plan view taken on the line 3—3 of Fig. 2,

Fig. 4 is a top-plan view with parts in section showing the time switch, the dial being partly broken away,

Fig. 5 is a detail view on an enlarged scale with parts broken away showing a frame pro-

vided with the fluorescent screen, the Röntgen box and means for holding the said Röntgen box in inoperative position, and

Fig. 6 is a diagram showing the electric connection of the apparatuses used in the system. 55

In the example shown in the drawings the controlling apparatus comprises a table 2 having a case 1 mounted thereon, the top plate 3 of the said case consisting of insulating material such as marble. On a shaft 30 mounted within the said case a switch drum 6 is mounted, and the end of the said shaft projecting through the top plate 3 carries a hand lever 4 provided with a pointer 31 playing over buttons *a*, *b*, *c*, *d*. Further, a time switch 5 is mounted on the plate 3, the object of the said switch being to determine the time for preparing the apparatus and the time of the exposure. The drum 6 carries six contact segments I, II, III, IV, V, VI, of different circumferential extent, adapted to make contact with six brushes I', II', III', IV', V', VI'. The segment I is of such circumferential extent that it is in constant contact with the brush I', the remaining segments making contact with the corresponding brushes dependent on the position of the drum. 70 75

Above the drum 6 the shaft 30 carries a notched disk 7 the notches 37 of which are engaged by a roller 8 carried by a lever 9 rockingly mounted on the case 1 at 10 and acted upon by a spring 11 tending to hold the same in engagement with the disk 7, the object of the said roller and lever being to insure the correct positions of the contact segments of the drum 6 relatively to the brushes. The different positions of the contact segments of the drum 6 relatively to the brushes and corresponding to the positions 90 of the lever 4 relatively to the buttons *a*, *b*, *c*, *d* have been indicated in Fig. 6 by broken lines *x*, *y*.

On a frame 24 providing a horizontal guide a frame 22 is mounted for being movable in lateral direction, and in its lower section the frame 22 carries a fluorescent screen 23. The vertical side members of the frame 22 provide guide ways 22' for a frame 21 adapted to receive a box 41 containing a sensitized 95 100

plate. The frame 24 is ordinarily mounted on a stand (not shown). To the top part of the frame 21 a string 25 is attached which is trained on rollers 38, 39 mounted on the frame 22, and which carries a button 40 at its free end. The frame 2 is adapted to be lifted into the position shown in the figures by means of the string 25, and it is held in the said position by means of an electrically controlled locking mechanism. As shown the said locking mechanism comprises an electromagnet 19 mounted in a bracket 42 fixed to the outside of one of the vertical members of the frame 22; the armature 20 of the said electromagnet is rockingly mounted at 43 and is formed with a nose 20' projecting, when the electromagnet is deenergized, through the said member of the frame 22 and into the guide way 22' and into position below the elevated frame 21. When energizing the electromagnet 19 the armature 20 is attracted so that the nose 20' releases the frame 21 of the box, which therefore drops by gravity, so that the box 41 is in position in front of the screen 23.

The upper section of the frame 22 is covered by a lead plate 44 adapted to protect the elevated box 41 from the Röntgen rays.

The time switch 5 comprises two pointers 13 and 14 movable across the dial 12, and the said dial is provided with marks representing fractions of seconds. Below the dial there is a clock work (not shown), which tends to return the pointer 13 into zero position after it has been turned by hand from its zero position and in the direction of the arrow 16. The pointer 13 carries a finger 32 which projects downwardly therefrom, and which is adapted to engage a contact spring 18 carried by the pointer 14 when being returned into zero position by the clock work for carrying the same along and into zero position, the pointer 14 having been moved through a smaller angle than the pointer 13, as will be described hereinafter. The pointer 13 is adapted to be set on any of the marks of the dial representing time by means of a button 15 fixed to its spindle 45. A button 17 carried by the end of a spindle 46 is provided for coupling the pointers 14 and 13 by means of coupling means not shown in the figures, for simultaneously turning both pointers out of the zero position by rotating the button 15 and simultaneously depressing the button 17. The hub of the pointer 14 is engaged by a brush 36 connected to a lead 59, and the hub is formed with an insulating portion 47 disposed so that the brush 36 engages the same when the pointer 14 is in the zero position relatively to the dial. The clock-casing is connected with a lead 63. The pointer 13 is electrically connected with the casing through the clock work, while the pointer 14 is insulated from the said parts. When

the pointers have been turned away from the zero point of the dial the contact spring 18 closes the electrical circuit through 63, 5, 13, 32, 18, 14, 36 and 59, as soon as the pointer 13 has been removed by the clock work into engagement with the said spring 18, and the said circuit is interrupted as soon as the pointers 13 and 14 arrive in their zero position.

Ordinarily the time switch 5 is arrested by means of a locking hook 26' providing the armature of an electromagnet 26 disposed within the clock and engaging a locking cross 48 connected with the clock work. When energizing the electromagnet 26 the locking hook 26' is retracted away from the cross 48, so that the pointer 13 is released and allowed to be moved by the clock work mechanism towards the zero point of the dial. The pointer 14 controls the time of the photographic exposure, and the pointer 13 controls the time for the preparatory operations, viz. the setting of the box 41 in front of the screen 23 and the rising of the temperature of the filament of the Röntgen tube to the temperature required for the exposure, the time of the preparatory operations being the difference between the times set by both pointers. For example, in the position of the pointers shown in Fig. 4 the time of the exposure is about 0,11 or 1/9 second, and the time for the preparatory operations is about 0,28 - 0,11 = 0,17 or 1/6 second. When setting the pointers on the said marks of the dial I prefer at first to depress the button 17 and to turn the button 15 in the direction of the arrow 16 for simultaneously turning both pointers to the mark 0,11, and thereafter to release the button 17 and to continue only the movement of the pointer 13 to the point 0,28.

Fig. 6 shows the electrical connections of the system with an alternating current net 50, 51 having a neutral wire 52. The brush I' is connected with the lead 50. The brush II' is connected by a lead 53 with the terminal 70 of an autotransformer R of known kind having a single coil and serving to regulate voltage, as is known in the art. The brush III' is connected to a wire 54, 54' connected to the net wire 51 and including the primary of the heating transformer T¹ of the Röntgen tube T and two resistances R¹, R². A lead 55 connects a brush IV' with a point between the resistance R¹, R². The brush V' is connected by a lead 56 with the electromagnet 19 (Fig. 5), which electromagnet is further connected by a lead 58 with the neutral wire 52. The brush VI' is connected by a lead 57 with the electromagnet 26 (Fig. 4), which is likewise connected by the lead 58 with the neutral wire 52, the said neutral wire being further connected by the wire 63 with the casing of the time switch 5. The lead 59 connected to the brush 36 located within the clock includes a relay J¹ and it is

connected to the lead 57. The terminals 70 of the autotransformer R is further connected by a lead 60, 60' including a switch J with the net wire 50, and the other terminal 71 is connected by a lead 61, 61' with one terminal of the primary of the transformer T² for the working current of the Röntgen tube T, the other terminal of said primary being connected with the controlling lever 68 of the autotransformer R by lead 61' including a variable resistance R³. The resistance R³ is adapted to be short-circuited by means of a switch J³ connected in shunt therewith. The switches J and J³ are so connected with the relay J¹ by means of a rod 62 that they are closed when current flows through the relay J¹. The rod 62 is acted upon by a tension spring J² tending to open the switches J and J³.

The secondary of the transformer T² is connected by leads 64, 65 with the cathode and anode respectively of the Röntgen tube T and the secondary of the transformer T¹ is connected by leads 66, 67 with the heating filament of said tube.

While the whole system is disconnected from the source of alternating current the box 41 containing a sensitized plate is placed into the position shown in Fig. 5 and the time switch 5 is set as above explained.

Now the lever 4 is set with the pointer 31 on the button e (Fig. 1). Thus the segment IV makes contact with the brush IV', and the primary current flows through 50, I', I, IV, IV', 55, R², 54', T¹, 51, inducing in the secondary circuit of the transformer T¹ a heating current of sufficient intensity for taking photographs. Now this heating current is set to the necessary intensity corresponding to the character of the exposure by means of the resistance R². It will be understood that for example for taking a photograph of the skull of a person the Röntgen tube T must be heated more intensely than for taking a photograph of the hand. For the present the transformer T² supplying the working current of the Röntgen tube T is out of operation.

Thereafter the lever 4 is turned with its pointer 31 into position above the button b, so that the brush III' makes contact with the contact segment III, and the contact IV-IV' is interrupted. Now the current flows through the transformer T¹ and the resistances R¹ and R² connected in series, the sum of the said resistances determining the intensity of the heating current required for examination.

Now the system is in position for making an examination and a following exposure. For making an examination the lever 4 is set with its pointer in position above the button a. In this position the contact between the segment III and the brush III' is maintained, and in addition the segment II makes con-

tact with the brush II', so that heating of the Röntgen tube T for examination is continued and a second circuit is closed through 50, I', I, II, II', 53, R, 69, 54', T¹, 51, the secondary current of the autotransformer R flowing through 68, 61', R³, T², 61, 71. Thus the transformer T² supplies working current to the Röntgen tube which is operated so as to project the object on the screen 23 for examining the same.

If it is now desired to take a photograph, the lever 4 is turned from button a over b and c to button d. As the lever passes to the button b the contact II-II' is broken, and the operation of the tube is temporarily interrupted, and when passing from b to c, the contact III-III' is interrupted, and immediately thereafter the contact IV-IV' is closed. Therefore hereafter the primary current of the heating transformer T¹ flows exclusively through the resistance R², so that the Röntgen tube is heated by means of a stronger current, as is necessary for taking a photograph. Finally, when the lever 4 passes from c to d, the contact is maintained at IV-IV', and the contact segments V and VI make contact with the brushes V' and VI'. Therefore current flows from the lead 50 through I', I, V, V', 56, 19, 58 to 52; the electromagnet 19 attracts its armature 20 so

that the nose 20' releases the box frame 21, and the box 41 drops by gravity and places itself in front of the screen 23. Simultaneously, current flows from 50 over I', I, VI, VI', 57, 26, 58 to 52, so that the electromagnet 26 is energized and the locking cross 48 and the clock work is released by the hook 26' of the armature of the said electromagnet. Now the pointer 13 begins its movement in the direction towards the zero mark of the dial. Within the interval of the time between the beginning of the movement of the pointer 13 and the engagement of the pointer 14 thereby, the Röntgen tube is heated so far as is necessary for taking a photograph, and the box 41 gets into position in front of the screen 23. When the pointer 13 makes contact with the pointer 14 the finger 32 carried thereby makes contact with the spring 18, so that a current flows from 50 over I', I, VI, VI', 57, J¹, 59, 36, 14, 18, 32, 13, 5, 63 to 52.

The relay J¹ attracts the rod 62 against the tension of the spring J² and closes the circuit at J and J³, so that the resistance R³ is short-circuited. Now the primary current of the autotransformer R flows from 50 over 60, J, 60', R, 69, T¹ to 51 and its secondary current through 68, 61', J³, T², 61, 71. By thus short-circuiting the resistance R³ the current supplied to the transformer T² is sufficient for producing the current intensity necessary for taking photographs. As soon as the said connection has been made exposure begins, and it lasts until the pointers 13 and 14 moving in unison arrive on the zero mark of the

dial. Now the insulating portion 47 of the hub of the pointer 14 engages the brush 36 so as to interrupt the circuit including the relay J^1 . Therefore the relay J^1 releases the rod 62, so that the spring J^2 opens the contacts J and J^3 , and the resistance R^3 is again included in the circuit of the transformer T^2 . Thus the conditions necessary for projection of the object on the screen are established, and the exposure is finished. 10 Immediately thereafter the whole system can be switched out by hand for completely interrupting the operation.

An important feature of my invention resides in that by only operating the lever of a hand switch the system can be rearranged from the position for examination to the position for making an exposure, the operations being successively performed by the 15 action of the switch in the predetermined succession, so that erroneous manipulations are impossible. By setting the system to a definite time for performing the preparatory operations the heating wire of the tube is 20 heated to a definite temperature before the high voltage current is made operative. Thereby short-circuits around the tube are avoided which might be caused by the current being prevented from passing through 25 the tube by reason of insufficient heating.

While in describing the invention reference has been made to a particular example embodying the same I wish it to be understood that my invention is not limited to the 30 construction shown in the drawings, and that various changes may be made in the general arrangement of the apparatus and the construction of its parts without departing from the invention.

40 I claim:

1. A Röntgen apparatus, comprising means for making diagnostic examinations, including a voltage transformer and a resistance controlling the voltage of said voltage transformer, means for making exposures including means for short-circuiting said resistance, a controlling hand switch and a time switch adapted to be connected with said hand switch for temporarily operating said 45 means for short-circuiting said resistance.

2. A Röntgen apparatus, comprising means for making diagnostic examinations, means for making exposures including means for producing X-rays and a normally inoperative holder for a sensitized plate, a controlling hand switch, means controlled by said switch for throwing said holder into operation, and a time switch adapted to be connected with said switch for throwing said 50 X-ray producing means for making an exposure into and out of operation.

3. A Röntgen apparatus, comprising means for making diagnostic examinations including a voltage transformer and a resistance controlling the voltage of said volt-

age transformer, means for making exposures including means for short-circuiting said resistance of the voltage transformer and a normally inoperative holder for a sensitized plate, a controlling hand switch, 70 means controlled by said switch for throwing said holder into operation, and a time switch adapted to be connected with said hand switch for temporarily operating said means for short-circuiting said resistance. 75

4. A Röntgen apparatus, comprising means for making diagnostic examinations including a voltage transformer and a resistance controlling the voltage of said voltage transformer, means for making exposures including means for short-circuiting said resistance of the voltage transformer and a normally inoperative holder for a sensitized plate, a controlling hand switch, 80 means controlled by said switch for throwing said holder into operation, and a time switch adapted to be connected with said hand switch for temporarily operating said means for short-circuiting said resistance, 85 said means being designed for connection 90 with the contacts of said hand switch so that the operations to be simultaneously performed are controlled by the same operations of the switch.

5. A Röntgen apparatus, comprising 95 means for making diagnostic examinations, means for making exposures, means for preparing the exposure, a hand switch controlling the said exposure making means and preparing means, said means for preparing 100 the exposure comprising a time switch adapted to be connected with said hand switch and adapted when operated first to run idle a predetermined period of time and thereafter to throw said means for making an exposure 105 into and out of operation.

6. A Röntgen apparatus, comprising means for making diagnostic examinations, means for preparing exposures, means for making exposures comprising an X-ray tube, 110 a controlling hand switch, said means for preparing exposures comprising a time switch adapted to be connected with said hand switch and being under its control, a relay for throwing in the exposure current 115 of the X-ray tube, means connecting said time switch with said relay, said time switch having means for independently setting preparatory and subsequent exposure time and for automatically throwing said means for 120 making an exposure into and out of operation.

7. A Röntgen apparatus, comprising means for making diagnostic examinations, means for preparing exposures, means for 125 making exposures comprising an X-ray tube, a controlling hand switch, said means for preparing exposures comprising a time switch adapted to be connected with said hand switch and being under its releasing control, 130

a relay for throwing in the exposure current of the X-ray tube, means connecting said time switch with said relay, said time switch having an exposure time hand, a preparatory time hand, means for imparting an idle movement to said preparatory time hand during the preparatory time, and for bodily moving both hands during the subsequent exposure time.

10 8. A Röntgen apparatus according to claim 7, said time switch having means for carrying on said exposure time hand by said preparatory time hand.

15 9. A Röntgen apparatus according to claim 7, one of the hands of said time switch having means for coupling the hands for bodily movement.

20 10. A Röntgen apparatus according to claim 7, said time switch having means for carrying along said exposure time hand by said preparatory time hand, said means being simultaneously contacting elements.

In testimony whereof I affix my signature.

Dr. ROBERT FEISLY.
